REFRIGERANT VALVE

Willard T. Weaver, Chicago, Ill.

Application November 4, 1932, Serial No. 641,131

2 Claims. (Cl. 251—87)

My invention relates to valves, and more particularly to those used for the control of refrigerant gases, and my main object is to provide a valve which makes a tight closure at all times.

5 A further object of the invention is to design the novel valve with simple and effective means for the control of the refrigerant gases for service, inspecting and testing purposes.

A still further object of the invention is to provide a valve which utilizes ground contacting surfaces of maximum area without impairing the facilities for the passage of the gases, whereby to secure ample closure and capacity factors.

Another object of the invention is to embody 15 in the novel valve a screen for filtering and divesting the gases of solid particles and other impurities which may impair the passage of the gases through the refrigerating system.

An additional object of the invention is to construct the novel valve with few and simple parts which are firmly assembled and contribute to make the valve an efficient appliance.

With the above objects in view and any others that may suggest themselves from the specification and claims to follow, a better understanding of the invention may be had by reference to the accompanying drawing, in which—

Fig. 1 is a front elevation of the novel valve;

Fig. 2 is a side view from the left;

Fig. 3 is a section on the line 3—3 of Fig. 2;

Fig. 4 is a cross section on the line 4—4 of Fig. 1;

Fig. 5 is a horizontal section on the line 5—5 of Fig. 3; and

Fig. 6 is a vertical section on the line 6—6 of Fig. 4.

The control valve in domestic refrigerating systems forms a very important part thereof, functioning to permit or cut off the passage of the refrigerant gases, and to open communication with a branch pipe for testing purposes. Usually, valves for this purpose are made with a steel stem, a lead packing and a packing nut, this type of construction being conventional in needle valves. However, when the valve is used for the discharge function in the refrigerant system, it becomes very hot during the operating cycle, whereby the steel stem is expanded and the lead packing forced to expand by the stem. When the compressor of the system completes its operation and stops, the valve cools off. The steel stem will contract, but the lead packing does not, so that a slight space develops between the stem and the packing. This causes a small gas leak, and refrigerant gases being noxious, such a leak is more or less of a menace to those who approach or pass in the vicinity of

the refrigerator. A service man is usually called to find the seat of the trouble, this task being a disagreeable one and more or less dangerous, as the handling and testing of a leaky valve involves the escape of more gas to which the service man is subjected. Further, leakage of gas is frequently caused by the corrosive effects of the gas upon the steel valve stem, the latter becoming pitted to the extent that it sticks and cannot be closed tightly. Thus, it will be evident that the servicing of the control valve is a task which is more or less dangerous to the service man and requires expert and rapid handling if poisoning or suffocation is to be avoided. It has, therefore, been my intention to design the novel valve on principles eliminating the difficulties outlined above, whereby the valve may continue in service without requiring appreciable attention and providing a high factor of safety when any servicing or inspection thereof is necessary.

Referring specifically to the drawing, the novel valve is essentially composed of a base 10, and a head 11. These parts are preferably made of brass, and the meeting faces of the head and base are finished and ground to a flat fit. The head 11 is circular and is made with an external flange 11a in the zone of its assembly with the base, the flange being held to the latter by the application of a ring 12 which receives screws 13 whose shanks thread into the base as indicated in Fig. 5. To further insure the assembly against leakage, I cut the contacting surfaces of the head and base with a number of matching V-grooves 11x which are filled with oil before the parts are assembled.

The base is made at one side with an S-shaped passage 10a to the outer end of which is applied that pipe 15 of the refrigerating unit which feeds the gas to the valve. The inner end of the passage 10a opens directly upon the head 11, and is continued therein with a passage 11b. The latter takes a transverse course in the center of the head, as indicated at 11c, and a return continuation 11d in the direction of the base 10. Opposite the continuation 11d, the base is made with an L-shaped passage 10d, one of whose ends opens outwardly and receives an outlet pipe 14. In order that the joint of this pipe with the base may be hermetical, I groove the inner portion of the pipe annularly, as indicated at 14a and provide a matching circular groove 10b in the base 10. This groove is continued with a straight extension 10c opening at the outer end of the base. When the pipe 14 has been fitted, it is only necessary to pour

molten solder into the extension 10c whereby to fill the inner cavity formed by the grooves and seal the pipe to the base. A continuous passage is thus formed from the inlet pipe 15 through 5 the assembled valve for the refrigerant gas in order that it may be delivered to the next unit in the system.

The valve passage just described is fitted in its center portion 11c with a screen cylinder 16 10 which is intended as a filter for the refrigerant gas and prevents dirt and foreign solid matter and lint from passing through the valve. The valve head 11 has a tapped opening 11e in its outer side through which direct access is had 15 to the filter screen 16, that the latter may be removed for cleaning or replacement, and this opening is tightly closed by a screw plug 17 when the valve is in service. Also, the lower part of the passage 10a in the base 10 is formed 20 with a tapped discharge opening 10e for draining the valve of the gas in either the vaporized or liquefied state, this opening being closed by a screw plug 18 while in service. The inlet portion of the valve base 10 is widened with 25 perforated flanges 10f which apply for a fit or union with the similarly constructed part 15 in the conventional manner.

While the screws 13 serve to hold the head 11 firmly to the base 10 by means of the ring 12, 30 the pressure of the latter is such that the head 11 may be turned in one or the other direction with a fairly snug fit, the head being reduced on its outer side with parallel ledges 11f for the application of a wrench.

35 The novel valve is designed for the control of the flow from the passage 10a to the passage 10d by means of the head 11. The control does not only involve open and shut positions, but also communication with an auxiliary 40 duct 10g in the base 10 which leads to a gauge pipe 19. As shown, the head 11 is in a position to allow full communication between the 45 passages 10a and 10d. Looking at Fig. 3 with the position of the head 11 in mind, it will be seen that a clockwise quarter-turn of the head 50 will carry its passages 11b and 11d entirely away from the passages 10a and 10d of the base, effecting a complete shut off. The passages 11b and 11d appear finely dotted in their changed 55 positions. Should a test of the gas be desired, the head is turned from the original position only a short distance in a counter clock-wise direction, whereby to place the passages 11b and 11d in the positions indicated by dot and dash 60 circles. Here it will be seen that the passage 11d registers both with the base passage 10d and with the duct 10g, permitting a communication 65 between the outlet pipe 14 and the gauge pipe 19. At the same time, the passage 11b is 70 in partial registration with the passage 10a whereby to permit the gas to enter and continue through the valve. When it is necessary to replenish or charge the system with gas, the 75 charging is done by way of the gauge pipe 19 and into the passage 10d. To do this, the valve is given a further turn in the same or counter clockwise direction to the long dotted position. Here it is seen that the passage 11d has departed entirely from the passage 10d in the 80 base, so that the outlet pipe 14 is cut off. The 85 passage 11b has likewise departed from the passage 10a, but secures a connection with the latter by means of a small duct 10h opening on the 90 face of the base. The valve head thus forms 95 a connection between the pipe 19 and the pas-

sage 10a to fill the latter with additional gas.

It is seen from the above description that the course which the head 11 takes for all functions of the valve is approximately a half turn, and I have provided a simple means to limit the rotation of the valve head to the said course in the form of an arcuate slot 11g cut in the periphery 5 of the valve head and receiving the inner end of a screw 20 driven through the ring 12. In connection with this feature it will be advisable to 10 mark the head with suitable indicia representing the positions to which it may be set for the purposes outlined.

It will be seen that the above valve constitutes 15 a sturdy and compact appliance to replace the stem valve usually employed in the refrigerant gas line. The valve has no steel stem to corrode and stick and has but one moving part which makes a ground joint with the base of the valve. Further, the valve employs no packing, gaskets or 20 adjusting nuts, and its action requires but a half turn to accomplish all its functions, as compared to a number of turns in the case of the stem valve. Further, the valve is self-sealing and embodies a 25 screen which stops dirt, sediment and lint from passing into the condenser of the system to clog the line carrying the liquefied gas, allowing the passages to remain clear for the maximum efficiency of the valve. Further, in addition to the 30 broad surface of the ground joint, I employ the seal of the oil grooves, so that any oil passing through the system will be supplemented by such seal to prevent the leakage of gas. Further, the 35 novel valve offers less resistance to the passage of liquefied gases because it has open, large and communicating passages rather than the obstruction of a closing stem as in the standard valve. Such a stem usually becomes a barrier to the 40 passage of the liquefied gas because of the accumulation of rust scales, sediment, dirt or lint in the closing zone. Further, it is evident the novel 45 valve is made of few and simple parts and so constructed that it may be easily shut off in case of testing or charging, whereby to eliminate the 50 leakage of the noxious gas and the danger occasioned thereby. Finally, it is apparent that the valve may be easily taken apart or opened for inspection or repair without stopping the refrigerator or removing the gas.

55 I claim:—

1. A refrigerant valve comprising a base, a head grouped in flatly-ground relation to one end of the base, the latter having inlet and outlet passages opening on the head, the head having an internal passage adapted to communicate with said passages and being rotatable to remove its internal passage from communication with the 60 passages in the base, the latter having a by-pass duct from the inlet passage and opening on the ground surface at one side of the center of rotation of the head, the base also being bored from one side with a duct whose outer end is adapted to receive a gauge pipe and whose inner end opens on the ground surface at a point opposite the opening of the by-pass duct, the ends of the internal opening in the head being of such size as to bridge both the passages in the base and the openings of the ducts at the ground surface when the head is given a relatively short partial turn.

2. A refrigerant valve comprising a base, a head grouped in flatly-ground relation to one end of the base, the latter having inlet and outlet passages opening on the head, the head having an internal passage adapted to communicate with said 70 passages and being rotatable to remove its internal 75

passage from communication with the passages in the base, the latter having a by-pass duct from the inlet passage and opening on the ground surface at one side of the center of rotation of the head, the base also being bored from one side with a duct whose outer end is adapted to receive a gauge pipe and whose inner end opens on the ground surface at a point opposite the opening of the by-pass duct, one end of the internal

opening in the head departing from the outlet passage in the base, and making communication with the gauge pipe duct, and the other end of the opening in the head making communication with both the inlet passage of the base and the by-pass duct when the head is given a relatively long partial turn. 5
